Primary Examiner — Karen E Kearney*Assistant Examiner* — Debra Callahan(74) *Attorney, Agent, or Firm* — Dority & Manning, P.A.(57) **CLAIM**

The ornamental design for display screen or portion thereof with graphical user interface, as shown and described.

DESCRIPTION

The FIGURE is a front view of a display screen or portion thereof with graphical user interface showing my new design. The outermost broken line illustrates the display screen or portion thereof, while all other broken lines illustrate portions of the graphical user interface, text and icons, and form no part of the claimed design.
